HAIR TESTING DEVICE

Samuel Grant, Chicago, Ill., assignor to Helene
Curtis Industries, Inc., Chicago, Ill., a corpo-
ration of Illinois

Application February 24, 1949, Serial No. 78,209

4 Claims. (Cl. 73—160)

1

The invention relates to a novel apparatus and means for determining the time required for a given permanent hair waving solution to reduce human hair to a desired plastic state.

The process of cold permanent waving of hair, as it is generally practiced, is to wind strands of hair on suitable curler rods and subsequently saturate said strands with hair waving solution. The hair waving solution acts on the hair to reduce it to a plastic condition. When the solution has remained on the hair for a length of time previously determined to be necessary to produce the desired plastic condition, a neutralizing solution is applied to arrest action of the hair waving solution. It is important not to allow the hair waving solution to remain on a head of hair for too long or for too short a period of time.

Owing to the inherent differences in the structure of human hair, it has been an exceedingly difficult problem to determine, accurately, the length of time the hair waving solution is to remain on the hair to reduce it to such a condition as will insure its remaining in its curled state after the hair waving solution has been neutralized and the hair dried. This difficulty arises because a single strength hair waving solution is provided for use on all kinds of hair and only the duration of the application is varied. Prior to the present invention, the processing time has been by guess-work. As a result, the hair frequently is over or under processed. Because the duration of treatment with a given hair waving solution is very critical, it is one of the objects of the present invention to provide an apparatus for determining this critical period.

The use of the apparatus of the present invention enables a beauty operator, using a single grade of hair waving solution for all kinds of hair, to determine accurately the length of time the solution should be allowed to remain on a given head of hair. The present apparatus is used by the beauty operator, prior to the processing of the hair on the head, to determine how long it takes for the hair waving solution to reduce a specimen of that hair from its normal or natural condition to that wherein the hair becomes sufficiently plastic to require the application of the neutralizing solution.

It is, therefore, another object of the invention to provide a novel hair testing apparatus which includes a container for holding a hair waving solution and wherein a shaft or shafts of human hair, selected from the head of the patron who is to receive the permanent wave, is immersed under tension in the solution and, more

5

particularly, to provide a novel arrangement for determining when the solution has reduced the specimen strand of hair to such a degree of plasticity as to allow it to stretch a predetermined distance. The time required to reduce the hair to such a plastic state as to enable it to stretch a predetermined amount determines the correct time interval which should elapse before the neutralizing solution is applied. The time required for plasticizing the specimen of the patron's hair to the critical point is carefully noted by the beauty operator and clocking of this time period is an important step in the use of the device of the present invention.

Other and further objects of the present invention will be apparent from the following description and claims and are illustrated in the accompanying drawing, which by way of illustration shows one embodiment and the principle thereof. Other embodiments of the invention embodying the same principle may be used and structural changes may be made as desired by those skilled in the art without departing from the present invention and the purview of the appended claims.

The figure in the accompanying drawing represents a front elevational view of the apparatus while in use, partly broken away to show parts in section.

Referring specifically to the disclosure in the drawing, the apparatus includes a horizontal support 11 suitably apertured to receive therethrough a tubular fitting 12. The fitting is secured in the opening as by means of a washer 13 and nut 14 threaded upon the upwardly projecting end thereof and a nut 15 threaded upon said fitting below the support 11. A clamp bracket 16 is firmly mounted about the tubular fitting 12 between the support 11 and nut 15. This bracket includes a plurality of downwardly extending spring fingers 17 normally drawn into a contracted relationship by means of a coil spring 18, or other means, surrounding the free end portions of said fingers. The spring fingers 17 are adapted to receive and firmly embrace the upper end of a test tube 19, or like container, when the latter is thrust upwardly through an opening 21 in a guide plate 22 spaced below the support 11. The test tube 19 is adapted to contain some of the hair waving solution to be used on the patron's hair and is so mounted as to be readily withdrawn from the spring fingers 17.

A rod 23 extends freely through the axial opening 24 in the tubular fitting 12. This rod depends below the bottom end of the tubular fitting and, as shown, carries on its reduced lower end

a spring clamp 25 which may be of any conventional construction but preferably is of a type having matching portions between which an object may be engaged and firmly retained.

The lower end of the tubular fitting 12 is formed with a reduced diameter 26 which provides a mounting for a second spring clamp 27 which may be constructed substantially like the clamp 25. The clamps 25 and 27 are therefore movable relative to each other, vertically, in such manner that the distance between said clamps may be varied.

The rod 23 extends upwardly beyond the upper end of the tubular fitting 12 and is provided on its upper end preferably with a flange 28. A vertical wall 29, which may constitute one wall of a housing supported by the horizontal support 11, extends upwardly from said support and is provided in the region of the flange 28 with a transparent panel 31. The panel 31 affords means whereby the flange 28 may be viewed.

To use the apparatus, a hair shaft 32 is removed by the beauty operator from the head of hair to be waved and is clamped adjacent its ends in the clamps 25 and 27. At the time of clamping the hair shaft in place, the test tube 19 is removed and the rod 23 is moved upwardly into substantially the position illustrated in full line. If desired stop means may be provided to limit movement of the rod 23 upwardly. When so positioned its flange 28 is in registering alignment with an index marking 33 on the transparent panel 31. It should be obvious that with the hair shaft clamped firmly in clamps 25 and 27, said hair shaft is tensioned under the weight of the clamp 25 and rod 23. The weight of the rod 23 and its clamp 25 is critically calibrated and it preferably weighs two and one-half grams. This constitutes enough weight to maintain the shaft of hair tensioned sufficiently for the purpose of making the instant test.

The container 19, containing some of the same hair waving solution that is to be used on the head of hair to be waved, preferably at a temperature of 80° F., is replaced through the guide opening 21 and is secured by the spring fingers 17. When so positioned, the tensioned portion of the hair shaft is completely immersed in the solution. The solution begins immediately to act chemically on the hair shaft. Such action reduces the hair to a plastic state and, during the initial period of reduction, the weight of the rod 23 and clamp 25 causes the plasticized hair to stretch rather slowly. However, the rate of reduction and stretching is accelerated considerably after the initial or preliminary stretching. When a plasticized strand has stretched one-third its original length, it is sufficiently plastic for the purposes of cold permanent waving. Obviously, a strand of fine porous hair having a high degree of absorptivity will plasticize and stretch in a much shorter time than a strand of coarse hair having a low degree of absorptivity.

The time interval elapsed between the immersion of a specimen strand of the hair in the hair waving solution and its becoming sufficiently plastic to stretch a predetermined distance is critical in the actual hair waving operation. It is, therefore, essential that the beauty operator be apprised of the time elapsed. This is facilitated by providing a second mark 34 on the transparent panel 31. This mark is spaced from the mark 33 a distance corresponding to one-third

the initial length of the hair strand under tension.

It should be quite evident at this time that if the operator watches the panel 31 she is immediately informed when the hair strand has been reduced to the desired degree of plasticity, this being indicated by the lowering of the flange 28 into register with the lowermost marking 34. The time elapsed from the initial immersion of the strand in the hair waving solution and the positioning of the flange 28 at the mark 34 is clocked by the operator. This time interval is then used by the operator to determine the length of time during which the hair waving solution is to be allowed to remain on the curls on the head during the hair waving operation.

The waving of the hair on the head preferably is accomplished substantially as follows:

The strands of hair on the head which are to be curled are first wound on curler rods. If desired, the strands may first be wetted with water or with a slight amount of hair waving solution. Initial wetting with a small amount of solution is not sufficient to chemically act on the hair to any appreciable extent. After each curl is wrapped on a curler rod, the operator then very thoroughly wets the curls with the hair waving solution. This application of the hair waving solution is very heavy and closely approximates the condition of saturation existing during the pre-testing of the hair strand in the apparatus described hereinabove.

The length of time a curl is subjected to the action of the hair waving solution corresponds substantially to the period of time previously found to be satisfactory during the test conducted with the instant apparatus. For example, in cold waving a cap is placed over the wound curls during the processing time. This tends to raise the processing temperature about 10° above the testing temperature. As a result of this increased temperature, the processing time under certain conditions may be shortened somewhat. Thus, if the testing time at 80° F. is from one to thirteen minutes, the actual time required at 90° F. may be substantially the same; whereas, should the testing time at 80° F. be nineteen minutes, the actual processing time at 90° F. may be but seventeen minutes. These time ranges and differentials may be furnished to the operator in the form of time charts supplied with the apparatus. At the end of the critical time period, determined by previous test and reference to the chart, the neutralizing solution is applied.

It should be apparent that the instant method of testing a specimen strand of hair removed from the head of hair to be waved affords means whereby the hair waving solution furnished to the beauty operator may be used with excellent results on all kinds and grades of hair. For example, a test of fine hair having a high degree of absorptivity will establish that the solution need remain on the hair for a shorter period of time than is required when coarse hair having a low degree of absorptivity is to be waved. It no longer becomes necessary for a beauty operator to guess as to the quality of the hair by a "feel test." Such manner of testing is very unsatisfactory owing to differences in absorptivity and porosity present in hair having substantially the same feel. Thus, under the present method, all guess-work is eliminated because a specimen strand of hair removed from the head of hair to be processed is tested in the instant apparatus by being subjected to the reducing action of the same

solution that is used in the process of actual waving of the hair on the head.

While the foregoing specification sets forth the apparatus of the invention in more or less specific terms, it should be understood that various changes may be made in the size, shape and kind of materials used in its construction, without departing from the spirit of the invention or the scope of the appended claims.

I claim:

1. In an apparatus useful for determining the time required to reduce a strand of hair removed from a head of hair to be permanent waved to such plastic state as to permit it to stretch a predetermined distance while it is immersed in the hair waving solution to be applied to said head of hair, the combination of, a fixed tubular element adapted to have one end portion of the hair strand secured thereto, a vertically movable element telescoped through the fixed tubular element and including a clamp located below said fixed element adapted to have the other end portion of said strand secured thereto while the element is in its uppermost position with the strand tensioned between said elements, a container for a hair waving solution, means to mount said container to immerse said tensioned strand in the hair waving solution, a gauge member carried on the upper end of the movable element, a transparent panel arranged in front of said gauge member, and a pair of gauge markings on said panel, said markings being spaced apart vertically a distance corresponding to the stretch desired so as to afford visual means to indicate when the desired plastic condition is attained.

2. An apparatus of the character described, comprising a container adapted to hold a hair waving solution, a stationary element fitted over the top of said container, said element being tubular and having a clamp thereon, a rod depending into said container freely through the tubular element, and a clamp at the lower end of said rod, said clamps being adapted to be engaged with opposite end portions of a shaft of hair to hold said hair tensioned and immersed in said solution.

3. An apparatus of the character described, comprising a container adapted to hold a hair waving solution, a stationary tubular element, spring fingers associated with said element to engage around the top of the container with the tubular element extending therein, a clamp on the lower end of said tubular element, a rod depending into said container freely through the tubular element, and a clamp at the lower end of said rod, said clamps being adapted to be engaged with opposite end portions of a shaft of hair to hold said hair tensioned and immersed in said solution.
4. An apparatus of the character described, comprising a container adapted to hold a hair waving solution, a stationary tubular element, spring fingers associated with said element to engage around the top of the container with the tubular element extending therein, said tubular element having a reduced outside diameter at its lower end, a clamp on the reduced diameter of said tubular element, a rod depending into said container freely through the tubular element, and a clamp at the lower end of said rod, said clamps being adapted to be engaged with opposite end portions of a shaft of hair to hold said hair tensioned and immersed in said solution.
